JASPER SNELL, OF POTTSVILLE, PENNSYLVANIA.

Letters Patent No. 77,119, dated April 21, 1868.

IMPROVED RAILROAD-SILL AND CHAIR.

The Schedule referred to in these Letters Patent and making part of the same.

TO ALL WHOM IT MAY CONCERN:

Be it known that I, JASPER SNELL, of Pottsville, in the county of Schuylkill, and State of Pennsylvania, have invented a new and improved Railroad-Sill and Chair; and I do hereby declare that the following is a full, clear, and exact description thereof, which will enable others skilled in the art to make and use the same, reference being had to the accompanying drawings, forming part of this specification.

This invention relates to an improved railroad-sill and chair, and consists of a sill of suitable material; and I prefer making it of iron, composed of a base-plate having inclined walls set upon it, forming a trough, in the bottom and near each end whereof is a mortise, in which is laid a spring.

A plate, provided with two-lugs on its under side, dove-tails into the trough; the lugs setting into the mortises and resting on the springs.

A T-shaped chair, having jaws at one end to fit the shape of the base of the rail, dove-tails into the trough, and sits upon one-half of the plate. One side of the base of the rail is then inserted between the jaws of the chair, and a corresponding chair is then dove-tailed into the trough, and embraces the other side of the base of the rail with its jaws. A sliding plate is then inserted in grooves in the walls of the trough, locking the whole.

A mortise in the sides of the trough enables the rail to rise and fall, by the operation of the springs and weight of the cars, and assists to hold the rail in place.

By the use of this sill and chair, the rail is held far more securely than by any means now used, and the elasticity given, by the use of the springs, will materially diminish the jolting of the cars; and the wear and tear of rails, chairs, sills, permanent way, and rolling-stock will be greatly reduced.

In the accompanying drawings—

Figure 1 is a vertical longitudinal section of my improved sill and chair, and

Figure 2 is a transverse section thereof at line $z-z$.

Similar letters of reference indicate corresponding parts.

A A is the base-plate of sill, having walls B B set upon it, inclined toward each other, as shown in fig. 2, but at sufficient distance apart to admit of the plate C and chairs D dove-tailing between them; as hereinafter described.

One end of the sill is closed by the wall E, and the other by the sliding plate F sliding in grooves f in the walls B and base-plate A.

The walls B are strengthened by trusses b, as shown in fig. 2.

In the mortises a in the base-plate A are placed the springs G, on which rests the lug c attached to the bottom of the plate C.

The plate C being dove-tailed between the walls B, and its lugs resting on the springs, the T-shaped chair D is then dove-tailed between them, and driven up against the wall E, with its jaws d d directed outward, the chair D resting on the plate C. The rail H is then placed upon the sill, its base, h, being inserted, across the walls B B, in mortises in the upper part of said walls fitted to receive it; one side of the base being inserted in the jaws d d of the chair D. The other chair D is then dove-tailed between the walls B, and embraces the other side of the base of the rail A with its jaws, and the sliding plate F is then inserted in the grooves f, locking the whole arrangement.

The chairs D are provided with a neck, d', having a rectangular vertical section, to allow the chair to move up and down between the walls B, according as the springs G are acted upon or released by the weight of the cars, and keep the neck of the chair home to the walls B B in every position.

I claim as new, and desire to secure by Letters Patent—

1. The base-plate A, walls B, and springs G, all substantially as and for the purpose set forth and described.
2. The plate C, dove-tailing between the walls B, and provided with the lugs c, substantially as above set forth and described.

3. The chairs D, dove-tailing between the walls B, and provided with the jaws d d , in manner substantially as above set forth and described.
4. The railroad-sill and chair, consisting of a base-plate, A, walls B, and plate C, resting on springs G, in combination with chairs D, furnished with the jaws d d , in manner and for the purposes substantially as above set forth and described.

JASPER SNELL.
